(57) **CLAIM**

The ornamental design for a pipe supporting device, as shown and described.

DESCRIPTION

The nature and intended use of the device is to support pipes, especially pipes running along a substantially horizontal surface.

FIG. 1 is a view of a pipe supporting device of the present invention;

FIG. 2 is a top view of a pipe supporting device of the present invention;

FIG. 3 is a bottom view of a pipe supporting device of the present invention;

FIG. 4 is a front view of a pipe supporting device of the present invention; and,

FIG. 5 is a side view of a pipe supporting device of the present invention.
